UNITED STATES PATENT OFFICE.

ANNA SCHUSTER, OF GOWER, MISSOURI.

MEASURING DEVICE.

1,229,798.

Specification of Letters Patent. Patented June 12, 1917.

Application filed April 8, 1916. Serial No. 89,837.

To all whom it may concern:

Be it known that I, ANNA SCHUSTER, a citizen of the United States of America, residing at Gower, in the county of Clinton 5 and State of Missouri, have invented certain new and useful Improvements in a Measuring Device, of which the following is a specification, reference being had therein to the accompanying drawing.

10 This invention relates to a measuring device or skirt marker, and has for its object the production of a simple and efficient means for efficiently marking a skirt without the necessity of a person marking the 15 same touching or pulling upon the skirt or other piece of material which it is desired to mark.

A still further object of this invention is the production of a simple and efficient 20 marker, the parts of which may be readily separated and the standard folded easily upon the support so as to facilitate the packing of the device for shipment or storing away.

25 With these and other objects in view this invention consists of certain novel combinations, constructions, and arrangements of parts as will be hereinafter fully described and claimed.

30 In the accompanying drawings:—

Figure 1 is a side elevation of the marker. Fig. 2 is a front elevation thereof.

Fig. 3 is a section taken on line 3—3, of Fig. 1.

35 Fig. 4 is a bottom plan view of the standard of the marker.

Fig. 5 is a top plan view of the base of the marker showing the standard folded downwardly.

40 Fig. 6 is a vertical section taken on line 6—6, of Fig. 1.

Fig. 7 is a top plan view of the clamp showing the manner in which the same is carried by the standard.

45 Fig. 8 is a section taken on line 8—8, of Fig. 2.

By referring to the drawings it will be seen that 1 designates the base which comprises a flat body having a centrally located 50 transversely extending slot 2 formed therein. A pair of brackets 3 are mounted upon the base 1 and are adapted to fit upon either side of the slot or aperture 2 as illustrated clearly in Fig. 5 of the drawings. A standard 4 is pivotally mounted between the brackets 3 as illustrated clearly in Figs. 1

and 2 of the drawings, and this standard 4 is provided with a projecting lower end 5, which projecting lower end 5 is adapted to abut against the wall 6 of the aperture 2 as 60 illustrated in Fig. 8 and limit the swing of the standard 4 in one direction. The aperture 2, however, is so constructed as to permit the standard 4 to be swung downwardly in one direction such as illustrated in dotted 65 lines in Fig. 8 of the drawings. A bracket 9 is adjustably mounted upon the standard 4, and this bracket 9 is provided with a loop portion 10, which loop portion is provided with apertures 11 for the purpose of permitting the standard 4 to pass therethrough. A clamping screw 12 is carried by the loop portion 10 of the bracket 9, and this clamping screw passes through a bearing block 13 as illustrated in Fig. 6. It should be understood that the clamping screw 12 may be 70 operated so as to bind firmly against the standard 4 and lock the bracket 9 in an adjusted position upon the standard 4. The standard 4 is provided with a plurality of 75 80 graduations formed thereon, ranging from one to seven and a half inches, although it should be understood that the graduations may be constructed according to the desire of the manufacturer of the device, and to 85 suit the use to which the device may be put. The bracket 9 carries an inverted bellows 14 at the outer end thereof, which bellows is provided with a discharge nozzle 15, which nozzle extends outwardly so as to have the 90 outer end 16 thereof on a line with the upper edge of the bracket 9 as indicated by the line A—A illustrated in Fig. 1. It should be understood that the upper edge of the bracket 9 is adapted to register with the 95 graduations upon the standard 4, thereby indicating the exact point upon which a mark will be made upon a skirt or other piece of material which it is desired to mark.

From the foregoing description it will be 100 seen that a very simple and efficient marker has been produced whereby the bracket may be adjusted to the desired height upon the standard, and also that the standard may be folded downwardly upon the base so as to 105 permit the device to be easily packed or stored away while not in use. It should be further understood that by means of the bellows 14 it will not be necessary for the operator to touch the garment which is being 110 marked as it would be likely to cause the same to sag at the place where the mark is

made, as the bellows 14 may be used to force powdered chalk or other substance through the spout 15 for the purpose of marking the garment 17 indicated in Fig. 1 of the drawings.

Having thus described the invention what is claimed as new, is:—

A device of the class described comprising a base, said base provided with an elongated slot, a bracket positioned upon each side of said slot and carried by said base, a standard pivotally secured between said brackets,

said standard provided with a depending end adapted to work in said slot and abutting against one end of said slot for limiting the swing of said standard in one direction, said standard capable of being swung downwardly in the opposite direction, and a bellows adjustably mounted upon said standard.
